UNITED STATES PATENT OFFICE.

HENRY HOCHEUTENER, OF WEST HOBOKEN, NEW JERSEY.

SHUTTLE-MACHINE EMBROIDERY-FRAME.

1,087,766.

Specification of Letters Patent.

Patented Feb. 17, 1914.

Application filed May 10, 1913. Serial No. 766,841.

To all whom it may concern:

Be it known that I, HENRY HOCHEUTENER, a citizen of the United States, and a resident of West Hoboken, in the county of Hudson and State of New Jersey, have invented a new and Improved Shuttle-Machine Embroidery-Frame, of which the following is a full, clear, and exact description.

This invention relates to improvements in frames for embroidery machines and to what are called section frames and embroidery frames, and has for an object to provide improved structures in which no waste spaces are presented.

Another object of the invention is to provide an improved section frame, designed to be formed with stiff bracing members at the ends and provided with thin bracing members intermediate the ends, so as to continually present a rigid section frame for receiving and holding in proper place the embroidery frames.

Another object of the invention is to provide an improved embroidery frame co-acting with the section frame for holding articles to be embroidered in proper position on the section frame and yet permit of ready removal at any time.

In carrying out the objects of the invention, the section frames may be made of any desired length and connected with the machine by suitable cleats or braces, so as to be firmly and rigidly held in place. The section frame is formed with a plurality of clamping screws for receiving the embroidery frames and for permitting the embroidery frames to be easily applied and removed. The embroidery frames are formed with ends interlocking with the clamping screws of the section frame and with side slots or grooves which accommodate article-clamping bars. These article-clamping bars are pivotally connected with one end of the embroidery frame, so as to be hinged or pivotally moved in and out of the grooves in applying and removing the article from the frame. These grooves may be made sufficiently large for accommodating the article-holding bars and a resilient clamping member, or may be made somewhat flexible, so as to pinch the article against the bar without the use of a resilient clamping member.

A practical embodiment of the invention is represented in the accompanying drawings forming a part of this specification, in which

similar characters of reference indicate corresponding parts in all the views.

Figure 1 is a top plan view of a plurality of embroidery frames, arranged in a section frame, one end of the section frame being shown broken away; Fig. 2 is a top plan view on an enlarged scale of an embroidery frame, an article being arranged in the frame; Fig. 3 is a section through Fig. 2, on line 3—3, same being shown on an enlarged scale; Fig. 4 is a section through Fig. 2 on line 4—4, same being shown on an enlarged scale; Fig. 5 is a sectional view similar to Fig. 4, but showing a modified form of the invention; Fig. 6 is a perspective view of the embroidery frame; and Fig. 7 is a top plan view of part of the modified form of section frame.

Referring to the accompanying drawings by numeral, 1 indicates a section frame formed with side angle bars 2 and 3 and end angle bars 4. A plurality of bracing bars 5 are arranged between the ends of the frame, so as to stiffen the frame. Bars 4 and 5 are comparatively thin, so that if it is desirable bars could be arranged at spaced intervals for preventing any swaying or bowing of bars 2 and 3. If desired frame 1' could be used as for instance in Fig. 7, in which heavy end bars 4' are utilized for properly holding the frame rigidly in place. When the heavy end bars 4' are used, the intermediate bracing bars 5 may be eliminated. In this form of section frame, an embroidery frame must be omitted at each end, while in the preferred form of section frame shown in Fig. 1, the embroidery frame will properly fit against the end bars 4. Arranged in the ends of section frames are notches 6, designed to accommodate a retaining strip 7 which overlaps adjacent section frames and properly holds the various section frames alined and correctly in position in the machine. This strip 7 may be screwed, bolted or otherwise rigidly secured in place without departing from the spirit of the invention.

Arranged along the section frame are a plurality of stops 8, preferably in the form of screws, so as to engage the notch 9 in the respective embroidery frames 10. The stops 8 are arranged in bars 2, while in bars 3 are arranged clamping screws 11, preferably formed with winged tops, so as to be easily operated. The screws 11 are formed with bosses, so as to fit over the end 12 of their

respective frames 10, while the body of the screw passes through the notch 13. The notches 13 are made comparatively long so that when the frames 10 are applied or removed, the same will permit the proper longitudinal movement of the frame in order that the notch 9 will clear the stops 8, after which the frames may be moved longitudinally so that notch 9 will slide beneath the head of stops 8. The screw 11 then may be tightened so as to clamp the frames properly in place.

The frames 10 may be formed of as many parts as desired without departing from the spirit of the invention, but preferably they are formed with a body having one piece and with the remaining parts connected therewith by rivets, screws or other suitable securing means. The body 14 is formed with ends 12 and 12', in which are arranged notches or slots 13 and 9. Notch 9 is cut away at 9', so as to more easily accommodate the head of stop 8, shown in Fig. 1. In forming the frame 10, the end members 12 and 12' are connected by longitudinal bars 15 and 16, substantially U-shaped in cross section, whereby grooves or slots 17 and 18 are provided. These grooves or slots are designed to accommodate clamping arms 19 and 20. Around these clamping arms are arranged rubber gripping means 21, as shown for instance in Fig. 4. The rubber tube 21 is preferably somewhat compressed so as to properly grip the work 22 and hold the same stretched tight across the frame from bar 15 to bar 16 as shown in Fig. 2. The needles of the machine may work freely in space between bar 15 and bar 16. If it is desired to work a design as shown in Fig. 2, the article 22 is arranged as shown in Fig. 2, but if it should be desired to work a design with its widest part extending in a direction at right angles to that shown in Fig. 2, the article 22 is turned substantially 90° and the needles will then properly act for working the design. The arms 19 and 20 are pivotally connected at 23 and 24 to a rigidly secured cross brace 25, though if desired, they could be secured directly to end 12. End 12' carries a cross bar 26 on which is pivotally mounted hook members 27 and 28, designed to hook over the ends of arms 19 and 20. Arranged at end 12 of each of the frames 10, is a clamp 29, formed with a body 30, having depending ears 31 and a biting nose 32. The biting nose 32 is adapted to bite or pinch article 22 against end 12 for assisting in holding the article properly in place and in the proper stretched condi-

tion. The ears 31 have passing therethrough a shaft 33 mounted in ears 34, preferably formed integral with end 12. A spring 35 surrounds shaft 33 and has one end pressing against end 12 and the other against body 30, so as to normally press nose 32 against end 12.

In the construction of the section frame 1 and the detailed construction of the embroidery frames 10, it will be noted that the embroidery frames may be readily applied and removed whenever desired. For instance, any particular embroidery frame may be removed and again applied without in any way molesting or working upon any of the remaining frames.

Having thus described my invention, I claim as new and desire to secure by Letters Patent:—

1. In an embroidery frame of the class described, the combination with a section frame having clamping pins, of a frame formed with a body having end members and grooved connecting members, said end members being formed with notches adapted to straddle said pins, whereby said body is removably mounted on said section frame, and pivotally mounted clamping bars co-acting with said grooved connecting members for clamping an article to said body.

2. In an embroidery frame of the class described, the combination with a section frame having a stationary pin on one edge formed with a head, and an adjustable pin on the opposite edge formed with a head, of a frame for receiving an article, said frame comprising a body formed with end members and connecting grooved bars, said end members having notches therein, one of said notches being deeper than the other, whereby the deeper notch is caused to slide over one of said pins so that the opposite end of the body may be substantially flush with the pin on the opposite side of the section frame, said section frame being adapted to be moved over said last mentioned pin so that the end of the body will straddle said last mentioned pin, hinged bars adapted to fit into said grooved members, and hooked members for holding said hinged bars in place.

In testimony whereof I have signed my name to this specification in the presence of two subscribing witnesses.

HENRY HOCHREUTENER.
